Attorney

UNITED STATES PATENT OFFICE.

ROBERT WILLIAMS, OF HAVRE DE GRACE, MARYLAND.

FIRE-ESCAPE.

SPECIFICATION forming part of Letters Patent No. 576,390, dated February 2, 1897.

Application filed May 11, 1896. Serial No. 591,159. (No model.)

To all whom it may concern:

Be it known that I, ROBERT WILLIAMS, a citizen of the United States, residing at Havre de Grace, in the county of Harford and State of Maryland, have invented certain new and useful Improvements in Fire-Escapes; and I do hereby declare the following to be a full, clear, and exact description of the invention, such as will enable others skilled in the art to 10 which it appertains to make and use the same.

This invention relates to certain improvements in escapes, and it has for its objects to provide a support for a flexible ladder, which support can be readily and securely fastened 15 within a window and which is provided with handholds to assist a person in descending, and also to provide a flexible hand-rail extending the entire length of the ladder to enable a person to descend with safety.

20 To this end the invention consists of a support composed of an integral metal rod bent, as hereinafter explained, so as to form a horizontal rail and vertical handholds, the bent ends of the horizontal rail being adapted to 25 engage the inner sides of a window-frame or other opening, the intermediate bent portions, that is, the portions between the horizontal and vertical rails, forming arms which will project from the window to support the ladder, as more fully hereinafter described; and the invention further consists in providing the ladder at suitable points with a series of 30 brackets or projecting arms having perforations near their ends, through which extend 35 ropes which are suitably confined at their upper and lower ends, as more fully herein-after set forth.

The before-mentioned objects are attained by the means illustrated in the accompanying drawings, in which like letters indicate like parts in the respective figures, and in which—

Figure 1 illustrates a perspective view of a window and my improved ladder-support, ladder, and hand-rail in position; and Fig. 2 represents a perspective view of the support detached.

Referring to the drawings, the letter F indicates the ladder-support, which consists of 50 a metallic rod bent, as indicated by the let-

ters *d* and *c*, so as to form a horizontal rail *a* with projecting arms *e* and vertical arms *g*, the said arms *g* being bent to form eyes *b* for the purpose more fully hereinafter explained.

The upper end of the ladder is attached to 55 the arms *e*. The said ladder consists of a series of polygonal blocks *B*, bound at suitable intervals between the ropes *G* by means of binding-cords *H*, as shown in Fig. 1 of the drawings.

The letter *A* indicates the steps or rungs of the ladder, which are secured between each set of blocks, as shown in Fig. 1. Each alternate set of blocks is provided with outwardly-projecting arms or brackets *C*, which are perforated near their outer ends and through 65 which extend ropes *I*, which form hand-rails for a descending person when the ladder is in position. The ropes *I* at their upper ends are fastened to the eyes *b* of the ladder-support 70 and at their lower ends are secured to the ropes *G*.

When not in use, it is evident that the apparatus can be folded compactly and placed in readiness for immediate use. When required for service, the support is placed in the window, with the arms *e* projecting from the same and resting upon the sill thereof, the ends *b* of the horizontal rail *a* sitting behind and engaging the side edges of the window 80 frame or opening. The ladder is then dropped and the parts assume the position shown in Fig. 1, affording a safe means of escape from a building, the handholds *g* and hand-rails *I* forming a continuous support to permit a person to descend with safety.

As thus constructed, it will be seen that a light, compact, and easily-operated fire-escape is produced, which is simple and almost impossible to get out of order and which will 90 cost but a nominal sum to construct.

Having thus described my invention, what I claim as new, and desire to secure by Letters Patent, is—

1. A support for a fire-escape ladder, the 95 same consisting of a metallic rod bent so as to form a horizontal rail *a*, with outwardly-projecting arms *e* and vertical arms *g*, substantially as and for the purpose specified.

2. A fire-escape comprising a support adapt- 100

ed to be secured within a window-casing, and having outwardly-projecting and vertical arms, a ladder constructed of blocks bound at suitable intervals between ropes, as described; brackets secured to said blocks having perforations in their outer ends, and ropes adapted to pass through said perforations and to be secured at their upper ends to the vertical arms of the support, and at their lower

ends to the ladder, so as to form hand-rails, substantially as described.

In testimony whereof I affix my signature in presence of two witnesses.

ROBERT WILLIAMS.
